ABSTRACT: A system for use particularly in multiple completion wells to facilitate the use of "PDT" (pumpdown tools). Two production strings are connected downhole by a crossover port. During normal producing operations the port is closed. When it is desired to use PDT, or pumpdown tools, the crossover port is opened, thereby establishing a circulating path down one string and up the other. The port is opened by merely applying pressure in one of the strings.

RETRIEVABLE CIRCULATING VALVE INSERTABLE IN A STRING OF WELL TUBING

BACKGROUND OF THE INVENTION

Field of the Invention

This invention relates to a completion technique particularly for multiple completion wells. It relates especially to an improved means of opening and closing a crossover port between two strings of production tubing to facilitate the use of pumpdown tools.

Setting of the Invention

A recent development in offshore well completion is the completion of such wells where the well head assembly and production control units are positioned beneath the surface of the body of water, and preferably close to bottom of the body of water. This is in contrast to another procedure for completing offshore wells in which a stationary platform is erected which is supported by the ocean bottom and extends to above the surface of the water. If the platform system is used, the completion procedure can be quite similar to those used on dry land but may also use PDT technique with crossover. However, when the well head assembly is placed on the ocean floor, a new set of problems is raised with respect to carrying out workover operations, maintenance or other operations in a completed well. In order to carry out some of the more simple workover operations, such as perforating a well casing or removing paraffin, it has become necessary to develop an entirely new line of well tools which can be pumped through a production line from some remote location which may be a mile or more away. These tools enter the well by passing down the tubing string to be subsequently selectively positioned to carry out the selected operations. After completing the operation, the tool in the tubing string within the well is ordinarily removed by a reverse circulation operation. These tools and techniques are commonly called through-the-flow-line-type operations or PDT equipment because they are pumped down through the production flow line string. There has been considerable literature on this type operation. Further, commercially available tools can readily be obtained, for example, from Otis Engineering Corporation, Dallas, Texas.

Although there has been considerable effort expended to date developing hydraulic PDT equipment, there are still certain areas where improvement is needed. One such area is in the adaptation of the system to multiple completion well, i.e., the wells are separately produced from more than one productive zone. The need exists for an improved system for providing a crossover between two production strings and means for opening and closing the crossover. This invention provides such improved means so that the two strings can be used for separate production with the port closed, or with the port opened it can be used to circulate PDT equipment.

BRIEF DESCRIPTION OF THE INVENTION

This is a device for use in PDT systems. In accordance with this invention at least two production strings are suspended in the well. Near the lower end a port means or passage connects the two strings. A standing valve recess is provided in at least one of the strings immediately below the crossover port. A special standing valve is provided. In ordinary operations the standing valve cage seals the port and independent production can be obtained through each of the production strings. When it is desired to use the system as a circulating system for PDT equipment, pressure is applied to the tubing having the standing valve. This shifts a valve means so that the crossover port means is opened. The circulation can then be conducted for transporting of PDT equipment in the usual manner.

In a preferred embodiment a standing valve housing having a port in it is positioned adjacent the crossover port. A standing valve cage or carrier is mounted inside the housing and is held in an upper position by a shear pin. When in this position the standing valve cage seals the crossover port. By applying

pressure to the string in which the standing valve is located, the shear pin is sheared and ports in the upper part of the standing valve cage are aligned with the ports in the crossover and in the standing valve housing. Thus, communication is obtained between the two strings. The standing valve and its housing can be pumped in or retrieved with latch-on or PDT equipment.

Various objects and a better understanding of the invention can be had from the following description taken in conjunction with the drawings.

DRAWINGS

FIG. 1 illustrates a downhole arrangement of a crossover port between two production strings and the retrievable standing valve in a position closing the crossover port means.

FIG. 2 is similar to FIG. 1 except that the standing valve cage has been shifted to open the port means between the two strings of tubing.

FIG. 3 illustrates a pumpdown tool locomotive for use in retrieving the standing valve and its housing.

Attention is first directed to FIG. 1 which shows a first tubing string 10 which can be called the short string and a second tubing string 12 which, for convenience, can be called the long string. The short string is provided to produce fluid from an upper formation 14 and the long string is provided to produce from a lower producing interval 16. A packer 18 prevents communication in the casing 20 between production from the two zones.

Near the lower end of the short string 10 is a crossover port 22 which, when open, establishes fluid communication between the short string 10 and the long string 12. A standing valve recess 24 having upwardly facing shoulder 26 is provided in the long string just below the crossover port 22. A short distance above crossover port 22 there is provided a latching groove 28 in long string 12. A retrievable tool for holding the standing valve is shown in the long string 12. This includes outer housing 30 resting on seat 26 of recess 24. The housing contains ports 32 which are on the same horizontal level as crossover port 22. These ports 32 are spaced around the housing and radial alignment is not necessary. Sealing means such as cups 34 and 36 are, respectively, placed below and above port 32 so as to prevent fluid communication from crossover port 22 up between the retrievable tool 29 and the wall of long string 12. Piston cups 35 are provided at the upper end of housing 30 to keep sand out of latching groove 28. The piston cups 35 also make it possible to pump the housing 30 and its associated parts back down the string 12.

Mounted within housing 30 is a standing valve cage 38. This valve cage means 38 serves a double function. Besides the ordinary function as a valve cage, it serves as a sleeve valve for closing and opening port 22. This cage valve means 38 is held in its upper position by shear pin 40. When in this position the lower part of the cage 38 acts as a sleeve valve and seals the crossover port 22 and port 32 of the housing so that fluid communication between the two strings is not permitted. Seals 44 and 46, above and below, respectively, port 32, are provided. Cage 38 has ports 39 in the upper end and when in the position of FIG. 1, ports 39 are above seals 46. The lower end of standing valve cage 38 is provided with a valve seat 48 and a ball valve 50. This permits production to flow upwardly through long string 12.

Housing 30 is held in place against seat 26 by latching dogs 52. These latching dogs 52 are mounted in the upper wall of housing 30 about pivots 60 and are biased outwardly. Notch means 28 are provided in the wall of housing 30 so that the latching dogs 52 can pivot about point 60. Latching dogs 52 also include tripping shoulders 64. It is noted that latching dogs 52 are below piston cups 35 and serve to keep the sand away from the latching dogs.

FIG. 1 showed the position of the standing valve cage during normal production operations. When it is desired to treat the two strings as a circulating string for the pumpdown tool, it is

necessary to open the port 22 between the two. Before the port is opened, both completions (through strings 10 and 12) are shut in. If wells are of equal pressure, merely shut wells in and shear pin in long string. If one well has more pressure than the other, enough back pressure would have to be maintained on system to prevent this well from flowing. Opening of port 22 is accomplished simply by applying sufficient pressure in long string 12 to shear pin 40. When this pin is sheared the standing valve cage is driven to the position shown in FIG. 2. At this time it will be seen that the port means 39 in the upper end of standing valve cage 38 is aligned with the port 32 of housing 30 and also with the crossover port means 22.

When the standing valve cage is in the position shown in FIG. 2, the system is then available or in a condition to be operated as the conventional PDT system; that is, fluid can be pumped down one string and up the other. It will be recalled that it is this completion of the hydraulic circuit which makes the system operable. A device sometimes called a locomotive and at other times called an operating tool is moved along one string of the circulating path. This operating tool or locomotive carries with it any of a number of tools for performing downhole operations, such as perforating guns, paraffin scrapers, etc. The locomotive and its associated tool are pumped down through whichever string it is desired to perform the operation. If the operation is to be performed in the long string 12 in which a retrievable tool is, it is normally desired to remove the retrievable tool before attempting the workover operation in that string. This is conveniently accomplished by pumping locomotive with its latch-on tool down the long string 12. To provide this, the locomotive is provided with a collet which is used for pulling the retrievable tool. Attention is directed to FIG. 3 which generally illustrates a locomotive for retrieving the housing 30 and its associated parts. This includes a locomotive section 70 and a lower latching portion 72. Lower latching portion 72 includes latching dogs 74. These latching dogs 74 are designed to latch into latching grooves 76 in the inner wall of the upper end of housing 30. There are "locomotives" commercially available and the one shown here is merely for purpose of illustrating the overall operations. Thus, as locomotives such as illustrated by numeral 70 and latching means 72 are well known, no more detail will be given. When it is desired to remove the retrievable housing 30 and associated parts, the locomotive of FIG. 3 is pumped down "long string" 12 in a known manner. When the locomotive reaches the housing 30, latching dog 74 latches into latching grooves 76. Just before this occurs though, the lower end of the plug 72 strikes unlatching shoulder 64 thus unlatching locking dogs 52. As soon as the tool is locked in, fluid is then circulated down short string 10 and back up string 12. This forces the locomotive to the surface and it brings with it the retrievable housing 30 and its associated parts. Once the retrievable tool 29 is removed, the locomotive and its operating tool are lowered down through long string 12 so that the desired operation can be performed.

After the various operations have been performed with the PDT equipment, it is then desired to rerun the retrievable tool 29. However, before this is done, the standing valve cage 38 is

placed on the position shown in FIG. 1 and a new shear pin 40 installed. The retrievable tool is then placed in the long string 12 and driven by hydraulic pressure to the position shown in FIG. 1. It will be noted that the shear pin 40 is of sufficient strength to permit the tool to be driven to the well bore. However, the shear pin is of such low strength that it can be sheared by the application of pressure as described above. When the tool is repositioned as shown in FIG. 1, normal production operations can again be resumed.

While the above preferred embodiment has been described with a great deal of detail, other modifications can be made thereto without departing from the spirit or scope of the invention.

I claim:

1. An apparatus to facilitate the use of through-the-flow-line tools in multiple completed wells which comprises:

a long string of tubing suspended in a well bore;
a short string of tubing suspended in a well bore;

a passage downhole between said long string and said short string, said passage having a first port opening into a said long string and a second port opening into said short string;

first seat means in said long string below said first port means;

a retrievable tool set on said first seat, said retrievable tool permitting unidirectional flow of fluid upwardly therethrough; and

said retrievable tool including valve means having a first position and a second position, said valve means when in said first position closing said first port to prevent the communication of fluid between said long string and said short string, and when in said position opening said first port.

2. An apparatus as defined in claim 1 in which said retrievable tool includes:

a hollow housing member having a port therein opposite said first port of said passage when said body member is seated on said seat means of said long string;

and said valve means including:

a standing valve in said housing member, said standing valve having a cage and a ball therein, said cage having ports near its upper end; and
shearable means holding said standing valve cage in a first position so as to seal said first port, said standing valve cage when in a second position having its port aligned with said first port.

3. An apparatus as defined in claim 2 including latching dog means between said housing member and the inner wall of said long string of tubing.

4. An apparatus as defined in claim 3 including a latching groove in the inner wall of said housing member near its upper end.

5. An apparatus as defined in claim 3 including piston cup means mounted on the upper end of said housing member so that said housing member can be pumped down said long string.

UNITED STATES PATENT OFFICE
CERTIFICATE OF CORRECTION

Patent No. 3,554,281 Dated January 12, 1971

Inventor(s) John H. Ecuer

It is certified that error appears in the above-identified patent and that said Letters Patent are hereby corrected as shown below:

Column 1, line 36, "wall" should read --well--.

Column 1, line 47, "well" should read --wells--.

Column 2, line 41, "232" should read --32--.

Column 2, line 75, "tool" should read --tools--.

Column 3, line 8, after "shear" insert --shear--.

Column 3, line 16, "If" should read --It--.

Column 4, line 20, after "into" delete "a".

Column 4, line 32, after first "said" insert --second--.

Signed and sealed this 20th day of April 1971.

(SEAL)
